Patented Dec. 18, 1917.

UNITED STATES PATENT OFFICE.

JACOB B. ROSE, OF CLEVELAND, OHIO, ASSIGNOR TO THE MARVEL ACCESSORIES MANUFACTURING COMPANY, OF CLEVELAND, OHIO, A CORPORATION.

VALVE-GRINDING TOOL.

1,250,512.

Specification of Letters Patent.

Patented Dec. 18, 1917.

Application filed December 4, 1916. Serial No. 134,859.

To all whom it may concern:

Be it known that I, JACOB B. ROSE, citizen of the United States, residing at Cleveland, in the county of Cuyahoga and State 5 of Ohio, have invented certain new and useful Improvements in Valve-Grinding Tools, of which the following is a specification.

This invention consists in a valve grinding tool adapted to be operated by hand, all 10 substantially as shown and described and particularly pointed out in the claims.

In the accompanying drawings, Figure 1 is a plan view of the tool with the crank handle for operating the same in position 15 as in Fig. 3. Fig. 2 is a sectional horizontal plan on line 2—2, Fig. 3. Fig. 3 is a side elevation of the tool and a valve engaged thereby. Fig. 4 is a detail of the ball socket secured in the top of the casing. Fig. 5 is 20 a longitudinal sectional elevation of the complete tool on line 5—5, Fig. 1. Fig. 6 is a detail of the thimble which serves as a bearing for the actuating shaft.

The idea of the invention is to provide a 25 convenient and effective valve grinder for automobileists, particularly, and of a size which can be carried conveniently on the car with other needed tools, so that if a leaky valve or valve seat be found it can at 30 once be put in good working order and without calling in an expert to do the work.

To these ends the tool or device comprises a main shaft *s* which may have a total length of nine inches, more or less, and a casing or 35 head *c* of such size as to be comfortably grasped by the hand and in which said shaft is mounted to rotate or rather oscillate within suitable working limits, such oscillation being designed to give the valve a corresponding movement.

The said shaft carries a valve engaging wrench plate 2 or equivalent means in a slot in its lower extremity and which is secured in said slot by a cotter pin 3, or its equivalent, for convenient removal or reversal, the 45 said plate having teeth 4 at its opposite edges differently spaced apart to engage valves of different sizes.

The said head or casing is built in two 50 stamped sheet-metal sections or halves 5 and 6, respectively, which are constructed with corresponding diagonal or inclined inner edges adapted to match and one of which has spurs 7 at its inclined edge and the other 55 holes 8 in which said spurs are engaged and

locked. The said spurs are flexible and adapted to be opened if for any reason entrance to the interior of the head be required, and an offset flange on section 5 overlaps the plain edge of section 6.

The foregoing construction has the advantage of providing one of the two bearings for shaft *s* in each head section, the lower bearing being in section 6, which extends across the axis of said shaft to the 65 opposite side, while the upper bearing and thrust support for the shaft is in the top of section 5. The said bearings are reversely flanged or sleeved, and a socket 9 is seated from the inside in the upper bearing and carries a ball 10 in its top to take the direct thrust of the shaft. The said socket is flared or flanged inside against the wall of the head about the sleeve therefor and also has a plurality of spurs 12 engaged 70 through said wall to fix it in place, and a cotter pin 13, or its equivalent, through shaft *s* over its lower bearing in the casing *c* confines the shaft in working position.

Operation or oscillation of shaft *s* is effected by means of a yoke 14 engaged therewith at its divided end by cotter pin 15, or its equivalent, and said yoke is pivotally engaged at its closed end by a short arm 16 rigidly fixed on the short actuating shaft 17 75 with which the crank handle *h* is directly engaged. The said arm is bent inward toward its extremity at such inclination as will best promote the oscillation of the shaft through the rotation of the said actuating shaft by handle *h*, and the degree of oscillation is clearly shown in the respective views 2 and 5 and may be said to be equal to about 45 degrees or a quarter of a complete circle.

The said shaft 17 is supported in a thimble 18 set into a flanged opening in the side of casing *c* at a point directly opposite the pivot pin 15 of yoke 14 in said shaft *s*, and is fixed in place by spurs 19 through the 90 wall of the head similar to the socket 9. This provides also for removal of said thimble and socket when necessary but otherwise fixes them firmly in place.

The casing being struck up from sheet 105 metal it is possible to form unitary bearings therein for the respective shafts, and especially since the casing is divided on diagonal lines and which makes the part 5 one member with a bearing struck in its top, and the 110

part or section 6 another member with bearings in its bottom and side respectively. The diagonal division of the casing is also advantageous in assembling, since all the operating connections are inside, because it enables both shafts to be inserted in section 6 and the working connections between the same to be made and held together before the section 5 with its end thrust ball bearing 10 in cup or socket 9 is put in place. A like convenience occurs when for any reason the parts are to be separated, as for repairs or replacement.

What I claim is:

- 15 1. A valve grinding tool having a casing and a drive-shaft and a driven shaft mounted at right angles to each other therein, a yoke engaged with said driven shaft and a bent arm fixed on said drive shaft and pivotally connected with said yoke.
- 20 2. A valve grinding tool having a drive shaft and a driven shaft and a casing supporting said shafts, in combination with a yoke pivoted on said driven shaft and a curved arm fixed on the end of said drive shaft and pivotally connected with the otherwise free end of said yoke.
- 25 3. A valve grinding tool having a shaft provided with an open slot in its lower end and a reversible valve wrench in said slot constructed at opposite edges with teeth variably spaced apart to engage valves of dif-

ferent sizes, and means to support and actuate said shaft.

4. A valve grinding tool having a casing 35 adapted to be gripped in a hand and consisting of two struck-up sheet metal sections divided diagonally across the axis thereof from top to bottom, the outer of said sections provided with a shaft bearing in the top thereof and a cap in said bearing, and the inner section having bearings in its bottom and side respectively, the latter bearing having a thimble therein, a drive shaft through said thimble bearing and a driven 45 shaft in said other bearings, and said shafts operatively connected.

5. A valve grinding tool comprising a casing of a size adapted to be gripped in one hand and constructed in two sections united 50 on a line diagonal to the middle thereof from top to bottom and said sections having opposite bearings in their top and bottom respectively, a driven shaft centrally through said casing supported in said bearings, said top bearing being adapted to take the end thrust of the shaft, and a drive shaft through the side of the casing operatively connected with the said driven shaft and adapted to oscillate the same.

Signed at Cleveland, in the county of Cuyahoga, and State of Ohio, this 16 day of November, 1916.

JACOB B. ROSE.
